UNITED STATES PATENT OFFICE.

MICHAEL KELLY, OF BLOOMINGTON, ILLINOIS.

DRAFT DEVICE FOR LOCOMOTIVES.

SPECIFICATION forming part of Letters Patent No. 608,870, dated August 9, 1898.

Application filed November 6, 1897. Serial No. 657,671. (No model.)

To all whom it may concern:

Be it known that I, MICHAEL KELLY, of Bloomington, in the county of McLean and State of Illinois, have invented a new and 5 Improved Draft Device for Locomotives, of which the following is a full, clear, and exact description.

My invention relates to an improvement in devices intended to improve the draft in the 10 fire-box of a locomotive.

It consists of certain novel constructions which will be hereinafter described, and particularly pointed out in the claims.

Reference is to be had to the accompanying 15 drawings, forming a part of this specification, in which similar characters of reference indicate corresponding parts in all the figures.

Figure 1 is a longitudinal sectional elevation taken through the fire-box and boiler of 20 a locomotive and showing the draft-pipes in position; and Fig. 2 is a horizontal section taken through the fire-box, showing the draft-pipes beneath.

The object of my device is to supply an increased amount of air to the fire-box of a locomotive and at the same time to keep the ash-pan closed, so that there will be no possibility of escaping sparks setting fire to any of the 25 railway structures.

30 In the drawings, C represents the shell of a locomotive-boiler, and F the fire-box. The ash-pan G, located at the bottom of the fire-box, is of any usual construction and may be provided at front and rear with dampers g.

35 In using the pan with my device these dampers should normally be kept closed, as a sufficient amount of air is supplied through the pipes of my device to insure complete combustion.

40 In applying my device to a locomotive two funnels a are mounted upon the forward end of the locomotive, where the air will have a free and unobstructed access thereto. As the locomotive moves forward the air will flow into these funnels and be conducted into the pipes A', to and through the common pipe A, which is connected to both of the pipes A'. It will be conducted through this pipe into the ash-pan.

45 50 Similar funnels a' are located at the rear of the driving-wheels and extend outside the same, where the air will have free access

thereto. These funnels open forward and are connected with a pipe A³, which curves to a common connection with the pipe A², extending forward and entering the ash-pan from the rear. The air entering the funnels a' is carried forward through the pipe A² into the ash-pan. 55

The pipes A and A² connect with a T D. 60 From this T a vertical pipe a extends and is surmounted by a cylindrical head E. From this head a series of pipes e extend radially and are perforated upon their upper surface, so as to discharge the air upward beneath 65 the grate f.

The pipe A is provided with a damper B, which may be of any ordinary or desired construction, by which the pipe may be closed when desired, so as to prevent flow of air 70 therethrough. The pipe A³ may also be provided with dampers B, by which it may be closed and the flow of air therethrough prevented.

It is preferable when this device is used 75 that the dampers g of the ash-pan be kept closed. If desired, however, these dampers may be opened, so as to admit an additional quantity of air. When the locomotive is running, the air will be forced through the funnels a and a' and directed into the fire-box in a strong stream, which will cause a rapid 80 combustion of fuel upon the grate. The strength of this blast depends upon the speed at which the engine is running. 85

When the engine is stationary, the dampers g may be opened, if necessary. In using this method of supplying air to the furnace a more complete combustion will be obtained than by the ordinary means, and, moreover, 90 the escape of cinders and coals from the ash-pan will be entirely prevented.

Having thus described my invention, I claim as new and desire to secure by Letters Patent—

1. A locomotive having a closed fire-box and an air-supplying apparatus, comprising a pipe leading from the ash-pan forward to the end of the locomotive and terminating in an open funnel, a pipe leading from the rear end of the ash-pan and branching to each side, each branch terminating in forwardly extending funnels located outside of the engine parts, and a common connection of such 100

pipes with the ash-pan, whereby the air is discharged beneath the grate, substantially as described.

2. A locomotive, having a closed fire-box and a draft apparatus, comprising pipes leading from the ash-pan forward and to the rear, the pipe at the rear branching to each side and curving forward, the ends of said pipes being supplied with funnels opening forward and located outside of the engine-body, where the air will have free access thereto, a common receiver for the air from said pipes, located beneath the grates and discharging the air upward therefrom, and dampers in said pipes between their outer ends and their junctions, substantially as described.
3. A locomotive, having a closed fire-box and a draft apparatus, comprising a pipe lead-

ing from the ash-pan forward to the end of the locomotive and terminating in an open funnel, a pipe leading from the rear end of the ash-pan and branching to each side and terminating in forwardly-extending funnels located outside of the engine-body, a T receiving the forwardly-extending and rearwardly-extending pipes, a pipe extending upward from said T, and a head attached thereto having radial pipes connected to it and perforated upon their upper sides, whereby the draft is discharged beneath the grates, substantially as described.

MICHAEL KELLY.
